United States Patent

Des. 236,677
Patented Sept. 9, 1975

236,677

FOOD SERVING TRAY

Nicholas J. Pilger, Thousand Oaks, Calif., and Jay Edward Ryan, Wheeling, Ill., assignors to American Hospital Supply Corporation

Filed Jan. 7, 1974, Ser. No. 431,153

Term of patent 14 years

Int. Cl. D7—99

U.S. Cl. D7—38

FIG.6

FIG.7

FIG. 1 is a top plan view of a food serving tray embodying our design;

FIG. 2 is a bottom view thereof;

FIG. 3 is a side elevational view taken along line 3—3 of FIG. 1;

FIG. 4 is a side elevational view taken along line 4—4 of FIG. 1;

FIG. 5 is an end elevational view taken along line 5—5 of FIG. 1, the opposite end thereof being similar in appearance;

FIG. 6 is a plan view of the base section thereof with the cover removed; and

FIG. 7 is a plan view of the underside of the cover.

We claim:

The ornamental design for a food serving tray, substantially as shown.
